UNITED STATES PATENT OFFICE.

WILLIAM W. LEACH, OF PINELAND, TEXAS.

MECHANICAL STARTER FOR INTERNAL-COMBUSTION ENGINES.

1,165,008.

Specification of Letters Patent. Patented Dec. 21, 1915.

Application filed September 18, 1914. Serial No. 862,279.

To all whom it may concern:

Be it known that I, WILLIAM W. LEACH, a citizen of the United States of America, residing at Pineland, in the county of Sabine and State of Texas, have invented certain new and useful Improvements in Mechanical Starters for Internal-Combustion Engines, of which the following is a specification.

This invention relates to certain new and useful improvements in a mechanical starter for internal combustion engines.

The primary object of the present invention is to rotate the crank shaft of the engine by new and novel mechanical means of simplified and improved construction for the purpose of starting the motor or engine.

A further object of the invention is to provide means that can be easily and conveniently operated at a point remote from the engine, for instance, from the driver's seat of a motor car.

Further the invention aims to provide a starter, the parts of which are automatically returned after operation to their initial position preparatory to again rotating the crank shaft.

The above and other objects are attained by the mechanism illustrated in the accompanying drawings, in which:

Figure 1 is a side elevation of a conventional form of motor or internal combustion engine to which the present invention is applied, the latter being shown partly in section; Fig. 2 is an end elevation of Fig. 1; Fig. 3 is a detail view partly in section of the spring wound drum; Fig. 4 is an end view of Fig. 3 showing the spring of the drum; Fig. 5 is an end elevation partly in section of the drum on the engine shaft; Fig. 6 is a side elevation of the sleeve, and connected parts that are loose on the engine shaft; and Fig. 7 is an end view of Fig. 6.

The invention is illustrated in connection with a conventional form of motor 1, having the usual crank shaft 2, to which latter a drum 3 is rigidly fastened by a set screw 4. A sleeve 5 is mounted on the shaft 2 and has one end thereof provided with a drum 6 and its opposite end provided with a ratchet wheel 7. The sleeve is rotatably mounted upon the crank shaft 2 and the ratchet wheel 7 thereof is inclosed within the drum 3. A collar 8 is rigidly fastened to the crank shaft 2 and abuts the drum 6

of the sleeve to prevent endwise movement of the sleeve on the shaft 2.

For the purpose of rotating drum 3 from drum 6, a series of pawls 9 are arranged around the inner circumference of the drum 3 and are provided with balls 10 which pivotally fit into sockets 11 provided therefor in the drum 3. The pawls will, when the drum 6 is rotated in the direction of the arrow, engage with the teeth of the ratchet wheel and rotate the crank shaft 2 through the medium of the drum 3.

A stub shaft 12 is attached to any suitable support on the motor vehicle and is located substantially as shown in Fig. 1, and has a hollow sheave drum 13 rotatably mounted thereupon as more clearly shown in Fig. 3. In order to rotate the drum 13 a belt or strap 14 is attached, for instance by the rivet 15, to the periphery of the drum 13 and is wrapped a number of turns upon itself and around the drum 6.

A cable 16 has one end 16' fastened to the web 17 of the drum 6 and its opposite end 18 fastened to the flange of the drum 13, and is wound several times around the periphery of the latter.

In order to return the drum 6 to normal position after operation thereof, a clock-like coil spring 19 is fitted in the drum 13 and has one end 20 attached to the inner circumference thereof, and the opposite end 21 attached to the stub shaft 12.

A cover 22 is fastened to the drum 3 to retain the pawls 9 in their socket bearings.

As shown in Fig. 6, the drum 6 has its outer side open and an end of the cable 16 passed through an opening provided therefor in the closed side or wall 17, which cable is knotted or otherwise provided with a projection that engages wall 17. This structure allows the cable to be easily secured to drum 6 and also enables the knot to be easily accessible through or from the open side of drum 6 should the cable break and consequently necessary to form a new knot thereon.

The end of the belt or strap 14 has a handle 23 attached thereto and located in close proximity to the driver of the vehicle so as to be accessible to the driver without his leaving his seat.

The operation of the starter is as follows: The driver grasps the handle 23 and exerts a pulling action thereon, thereby unwind-

ing the strap 14 from the drum 6, and as the strap is unwound, the cable 16 winds around the sleeve 5 and unwinds from the periphery of the drum 13. As the strap 14 is being unwound from the drum 6 and the latter is thus being rotated, the ratchet wheel which is carried by the drum 6 is rotated with the latter in the direction indicated by the arrow by reason of the pawls 9 dropping by gravity into engagement with the teeth of the ratchet wheel, the rotation of the ratchet wheel imparting movement to the drum 3 through the medium of the pawls 9, thereby spinning the crank shaft 2. When the cable 16 is being wound on the sleeve 5 and unwound from the drum 13 the latter is rotated, winding the spring 19 so that when the operator releases the handle 23 the spring 19 is released and rotates the drum 13 in the opposite direction thereby winding up the cable 16 around the drum 13 and unwinding it from the sleeve 5, which places the starting mechanism in position to again be operated to spin or rotate the crank shaft, since the unwinding of cable 16 from sleeve 5 causes the strap 14 to be rewound on drum 6.

What is claimed is:

1. In a starter, a drum for securement to the engine shaft having interior pawls, a sleeve rotatable on the shaft, a ratchet wheel on one end of the sleeve disposed within the drum and engaged with the pawls, a drum on the other end of the sleeve having its outer side open, a spring wound drum having a cable connected thereto at one end of the latter, a cover on the shaft drum extending

over the ratchet wheel, the closed side or wall of the sleeve drum having an opening therein, the opposite end of the cable being passed through said opening and being provided with an enlargement which engages said closed side or wall of the sleeve drum and is accessible through the open side of the latter, said cable being windable on the sleeve between said cover of the shaft drum and the inner side wall of the sleeve drum, and a strap connected to the sleeve drum to rotate the latter.

2. In a starter, a drum for securement to the engine shaft having interior pawls, a sleeve rotatable on the shaft, a ratchet wheel on one end of the sleeve disposed within the drum and engaged with the pawls, a drum on the other end of the sleeve having its outer side open, a spring wound drum having a cable connected thereto at one end of the latter, a cover on the shaft drum extending over the ratchet wheel, the opposite end of the cable being in connection with the wheel whereby the cable will be wound on the sleeve at points between and determined by the cover of the shaft drum and the inner side wall of the sleeve drum, and a strap connected to the sleeve drum to rotate the latter.

In testimony whereof I affix my signature in presence of two witnesses.

WILLIAM W. LEACH.
